UNITED STATES PATENT OFFICE.

AUGUST DINGER, OF UPLAND, CALIFORNIA, ASSIGNOR OF ONE-HALF TO IRA P. DINGER AND ONE-HALF TO HARY W. DINGER, BOTH OF UPLAND, CALIFORNIA.

RAILROAD-CROSSING.

1,371,872.

Specification of Letters Patent. Patented Mar. 15, 1921.

Application filed January 26, 1918. Serial No. 213,922.

To all whom it may concern:

Be it known that I, AUGUST DINGER, a citizen of the United States, residing at Upland, in the county of San Bernardino and State of California, have invented certain new and useful Improvements in Railroad-Crossings, of which the following is a specification.

This invention relates to new and useful improvements in railroad crossings, and the primary object of the invention is to provide a simple and efficient type of railroad crossing, that reduces the noise and jar, incidental to a car making the crossing, to a minimum.

Another object of the invention is to provide a railroad crossing of this character, which is provided with guard rails, consequently increasing the safety of the type of crossing, in addition to the advantage before set forth.

A further object of the invention is to provide a device of this character, which is easily and simply constructed, inexpensive to manufacture, and one which will be very efficient in operation.

With these and numerous objects in view, my invention consists of the novel features of construction, combination, and arrangement of parts which will be herein referred to and more particularly pointed out in the specification and claim.

In the accompanying drawings:

Figure 1 is a top plan of the improved crossing,

Fig. 2 is an enlarged fragmentary top plan thereof,

Fig. 3 is a disassembled detail in perspective showing the relation of the guide rails and dog, and

Fig. 4 is a fragmentary cross section therethrough.

In describing my invention, I shall refer to the drawings in which similar reference characters designate corresponding parts throughout the several views.

This railroad crossing comprises a suitable supporting plate 1^a upon which are mounted corner rails 1, which have their free ends connected with the main tracks, at the point of intersection of the main track rails, said rails being provided with four relatively stationary and short crossing rails which are designated by the numeral 2, which are positioned to align with the corner

rails, as clearly shown in Fig. 1 of the drawings. The end sections of the short rails 2 are cut away as shown at 3 for a purpose to be hereinafter more fully described.

This crossing is provided with sets of guard rails, designated generally by the numeral 4, each guard rail extending parallel with alining portions of the corner rails and the crossing rails disposed therebetween, and the ends of the guard rail are bent laterally as shown at 5, for a purpose which is well known in devices of this character. The guard rail 4 is yieldably connected with the adjacent portions of the corner rails, and crossing rails, by a transversely disposed bolt 6, upon which the same is slidably mounted. The ends of the bolt carry coil springs 7, so that when the guard rails are forced from their normal position adjacent the aforementioned rails, they will be under spring pressure, and consequently upon the wheel flange pressure being released, will spring back to their normal position, as clearly shown in Fig. 1 of the drawing.

Adjacent the sides of the rail corners are pivoted plates 8, which are eight in number, being positioned as clearly shown in Figs. 1 and 2 of the drawing, their outer ends having formed thereon upstanding portions 10 having one side 11 curved arcuately to form a sliding joint co-operatively engaging with the curved end portions 3 of the crossing rails 2. When the device is in normal position, these portions of the plates will be co-operatively related with the ends of the crossing rails, and form a continuation of the same. Each of the plates 8 is pivotally secured at 8^a to the plate 1^a and is connected with the adjacent end portion of the contiguous guard rail by connecting stud 12, that projects from the web of said guard rail, and is loosely connected with the plate as shown at 13. The guard rails which cross each other, are provided with cut-away portions with projecting plates 14 having co-operating inclined edges as clearly shown in Fig. 2 of the drawings, and two of said guard rails are cutaway on their under sides, as suggested at 4^a in Fig. 3, to permit the rails to cross each other and have limited relative movement.

As has been stated, the guard rails in this device, normally lie against the corner rails, and cross rails, but they are yieldably held

against the same, so that upon outward pressure, they are adapted to move laterally. Upon a car passing over the crossing, the parallel rows of guard rails will be moved laterally toward each other by the wheel flanges moving in between the corner rails, and the end of the guard rails. This lateral movement will be against the spring pressure as has been fully described, and also 10 the overlapping joint formed by the upstanding portion on the pivoted plates 8, and the ends of the transverse crossing rails, will permit this movement of the rail, as the portion on the plate will slide outwardly, said movement being directed by the coöperative arcuate faces of this sliding joint. This movement is transmitted through the connection between the guard rails and the plates and hence the upstanding portions of the undisturbed plates 8 and the other pair of guard rails that are then disposed transversely, being positioned against the other portions of the corner rails form a continuous tread portion for 20 the car wheels. As soon as the wheels pass over the crossing, the springs will return the guard rail to normal position.

Wear plates 14^a are preferably attached to the guard rails 4 inwardly of the recesses 30 14 therein.

From the foregoing description, taken in connection with the accompanying drawings, the advantages of the construction and of the method of operation will be readily 35 apparent to those skilled in the art to which

the invention appertains, and while I have described the principle of the operation of the invention, together with the device which I now consider to be the best embodiment thereof, I desire to have it understood 40 that this device shown is merely illustrative, and that such changes may be made when desired, as are within the scope of the claim appended hereto.

Having fully described my invention, 45 what I claim is new, and desire to secure by Letters Patent, is:

In combination with a street crossing, a supporting plate, corner rails supported on said plate, yieldably positioned crossing rails having curved end portions, and yieldably connected, U-shaped guard rails co-operating therewith and with said corner rails, angular plates having free, arcuate extensions, pivoted to the supporting frame 55 and adjacent the guard rails, co-operating with the curved end portions of the crossing rails, each of said arcuate extensions interfitting in a slot in the said guard rails, rigid connecting studs having angular slots 60 projecting from said guard rails and loosely connected to said angular plates, and wear plates riveted to said guard rails in proximity to said slot in the guard rail and overlying the free extremities of said arcuate 65 extensions.

In testimony whereof, I affix my signature hereto.

AUGUST DINGER.
